UNITED STATES PATENT OFFICE.

THEODORE A. FREEMAN, OF PHILADELPHIA, PENNSYLVANIA.

HAND-BAG OR SATCHEL.

SPECIFICATION forming part of Letters Patent No. 281,482, dated July 17, 1883.

Application filed June 1, 1883. (No model.)

To all whom it may concern:

Be it known that I, THEODORE A. FREEMAN, a citizen of the United States, and a resident of Philadelphia, Pennsylvania, have invented 5 Improvements in Hand-Bags or Satchels, of which the following is a specification.

The object of my invention is to make a cheap and serviceable hand-bag or satchel, especially intended as a book-bag for school 10 children; and this object I attain in the manner hereinafter set forth, reference being had to the accompanying drawings, in which—

Figure 1 is a perspective view of a satchel made in accordance with my invention, and 15 Fig. 2 a view showing another form of handle for the satchel.

The satchel comprises a bag, A, of any desired size or shape, and of any appropriate textile fabric. Near the upper edge of the 20 bag, on each side, are formed perforations b, protected by eyelets, and through these eyeleted perforations are passed cords d, the ends of which are secured by metallic fastenings f, thus forming loop-handles by which the satchel may be conveniently carried.

The satchel can be thus made very cheaply, and is strong and serviceable, these qualities rendering it especially available as a book-bag for school children.

I claim as my invention—

An improved book bag or satchel, comprising the bag A, provided with eyeleted edge perforations, b, and cord handles d, passing through such perforations, and having their ends secured by metallic fastenings, all substantially as set forth.

In testimony whereof I have signed my name to this specification in the presence of two subscribing witnesses.

THEODORE A. FREEMAN.
